UNITED STATES PATENT OFFICE.

WILLIAM ROSE, OF GAINSBOROUGH, ENGLAND.

APPARATUS FOR SECURING THE FOLDED PORTIONS OF PACKAGE WRAPPERS.

Application filed April 18, 1923, Serial No. 632,925.

To all whom it may concern:

Be it known that I, WILLIAM ROSE, a subject of the King of Great Britain, residing at Albion Works, Gainsborough, in the 5 county of Lincoln, England, have invented new and useful Improvements in Apparatus for Securing the Folded Portions of Package Wrappers, of which the following is a specification.

- 10 This invention relates to apparatus whereby the folded portions of package wrappers, which are to be secured by adhesive material, are retained in contact with each other until the said adhesive material has become sufficiently dry to give secure adherence of the 15 folded portions, the said apparatus being of the kind in which the wrapped packages are carried between endless travelling belts the opposed inner runs of which are caused 20 to exert resilient pressure upon the folded portions of the said articles until such time as adhesive material applied thereto has become sufficiently dry to secure the said folded portions. This invention has for its 25 object to provide an improved apparatus of the aforesaid kind whereby the folded portions of a succession of wrapped packages, which may vary in size, are more effectually retained in position by the inner runs 30 of the travelling belts. The invention consists in the improved construction of apparatus hereinafter described wherein the inner runs of the said belts are caused to resiliently bear upon the folded portions of 35 the articles by a series of rollers which are spaced apart behind and bear against the said inner runs, the said rollers of the two series being arranged in a zig-zag, or staggered manner relatively to each other, so 40 that packages of greater width than the distance between the opposed inner runs of the said belts will have its ends to which adhesive has been applied held down by the conjoint action of the belt on one side and 45 a roller on the other side. This invention is not limited to application to wrapped packages, but I will, for the purposes of description presume that it is to be applied to securing wrappers enclosing tablets of 50 chocolate, or the like, for example, but it is to be understood that it can be applied in other analogous cases, where it is desirable to hold portions of wrappers, or other articles, together until they adhere.
- 55 According to this invention a pair of properly tensioned endless travelling belts,
- bands, or the like, (I will refer to them as belts) is provided each of the said belts being carried by a pair of pulleys to which rotary motion is imparted to cause the belts 60 to travel along at the same speed and a series of rollers, (which I will refer to as bearing rollers) bearing against the inner run of one of the said belts and another series of bearing rollers bearing against the 65 inner run of the other belt. The axis of the rollers in each series are adjustably fixed and spaced apart a distance substantially greater than the depth of the ends of the 70 said packages to which adhesive has been applied. The series of bearing rollers appertaining to either one of the belts are arranged in a zig-zag, or staggered, manner relatively to the series appertaining to the other of the belts, so that the bearing rollers 75 of the series appertaining to either of the belts are in positions opposite the spaces between the bearing rollers appertaining to the series of the opposite belt.
- Between the said belts a runner strip may 80 be provided and supported so as to constitute the bottom of a channel or trough, of which the belts constitute the sides and this channel, or trough, may be provided with a 85 cover if desired.
- When articles, to which, or to the wrappers of which, adhesive has been applied, are fed between the belts, so that the parts to which adhesive has been applied are presented to the belts, as the articles are carried 90 along between the belts resilient pressure is exerted upon them by reason of the bearing rollers on either side acting against the band, on that side in opposition to the portions of the belt which are between the 95 bearing rollers at the other side.
- To adjust the distance apart of the belts and bearing rollers to suit the size of the articles being manipulated the series of the said bearing rollers at one side, or at both 100 sides, are mounted in a support, or in supports, which can be adjusted and fixed in the adjusted position upon the framing, or table, of the apparatus.
- In order that this invention and how it 105 may be performed may be well understood I will describe, with reference to the accompanying drawings, a construction in accordance therewith, premising that I do not limit myself to the precise details illustrated and 110 hereinafter described.

Figure 1 is a plan, Figure 2 is a side ele-

vation, with a portion of one of the belts removed, to shew the rollers between the runs, and Figure 3 is a transverse section on the line A—B Figure 1.

5 Each of the endless belts (marked 1 and 1^a) is carried by a pair of pulleys (marked 2, 2^a and 3, 3^a respectively) to which rotary motion is imparted by means of a main shaft 4, mounted in bearings 5 and 5^a, and 10 having, keyed thereto, toothed wheels 6, and 6^a, which engage toothed pinions (one of which (7^a) is seen in Figure 2) respectively secured to the spindles 8 and 9 of the pulleys 2 and 3, the said spindles being 15 rotatable in bearings supported in a bracket 23, secured to the base-plate, or table, 17, one of which bearings (marked 10) is seen in Figure 2.

The pulleys 2^a and 3^a at the opposite end 20 are rotatably mounted on spindles 11 and 11^a, respectively, which spindles are carried in slotted extensions (12 and 12^a) of the bracket 13 secured to the base-plate, or table, 17 by screws 24, so that the said spindles 25 can be adjusted in the slotted members 12 and 12^a to such positions that the desired tension can be given to the belts.

Rotary motion is imparted to the main shaft 4, from an electric, or other suitable, 30 motor, this motion being imparted to the pulleys, through the gearing described and thereby the belts 1, and 1^a are caused to travel along at equal speeds.

The articles (such for instance as 35 wrapped tablets of chocolate indicated at 15) are introduced by hand, or by any other suitable means, in succession, and in proximity to each other, between the opposed inner runs of the belts with the parts to 40 which adhesive has been applied next the belts which bear against those parts which in the instance mentioned are the folded portions of the wrappers and the belts carry the said articles along for delivery into any 45 suitable receptacle, or to any required place.

A bottom runner strip 16 is formed on, or carried by, the base-plate, or table, 17, and in conjunction with the belts constitutes a channel along which the articles 15 are conveyed by the said belts.

The articles will be carried along by and ejected, or passed, from between the belts without the said articles being damaged, or having undue pressure exerted upon them 55 even if some of them should somewhat differ in size from the others.

The series of rollers 18 and 18^a, are rotatably carried on studs, (marked 19 and 19^a respectively) secured to the bars 20 and 20^a, adjustably secured to the baseplate, or table, 17, by screws 21 passing through slots 22 and 22^a, in ear-pieces projecting from the bars 20 and 20^a.

The rollers 18 and 18^a are spaced apart 60 behind, and so as to bear against, the back

of the inner run of each of the belts 1 and 1^a so as to cause the said inner runs to exercise pressure on the opposite ends, or sides, of the articles to which adhesive has been applied as they are carried along by the 70 said belts.

The rollers 18 are not situated opposite the rollers 18^a, but are arranged in zig-zag, or staggered, relation thereto so that the rollers of either series are opposite the 75 spaces between adjacent rollers of the other series and therefore the articles, between the said belts, when one end, or side, of the articles is bearing against a portion of the belt, against which a roller bears, will, at 80 its opposite end or side, be pressed upon by a part of the opposite belt, which is between two adjacent bearing rollers, and thus the folds, or portions, to which adhesive has 85 been applied are held down by the conjoint action of the belts and the bearing rollers, the belts being tensioned so as to cause the said belts to exert the requisite resilient pressure on the ends, or sides, of the articles 90 as they are carried along between the belts. 95

By these means a succession of articles, such, for instance, as wrapped packages, blocks, tablets, or cartons, containing material (such for instance, as material in small particles, or in a powdered, or granular, condition; for instance, tea, baking-powder, or the like, or articles of a fragile character, such as tablets, of chocolate, cigarettes, or the like) can be carried along any desired 100 distance by the belts whilst resilient pressure is exerted upon the folds, or portions, to which adhesive has been applied, for as long as is necessary, to allow the adhesive to become sufficiently dry to effectually secure the said folds, or portions, without 105 damaging or breaking, the articles dealt with, even if their size should vary.

If desired, to facilitate the drying of the said adhesive and further ensure the adherence of the folds, or portions, to which it has been applied any suitable heating means may be employed; but as the heating means in itself does not form any part of this invention, it is not necessary for me to 110 describe, or illustrate, it.

What I claim is:—

1. In apparatus for securing the folded portions of package wrappers to which adhesive has been applied, a pair of endless travelling belts so arranged that the packages to be dealt with can be introduced and carried along between the opposed inner runs of the said belts; in combination with a series of rollers bearing against the inner run of one of the said belts and an other series of rollers bearing against the inner run of the other of the said belts, the axis of the said rollers in each series being adjustably fixed and spaced apart a distance substantially greater than the depth 120 125 130

- of the ends of the said packages to which adhesive has been applied and the said rollers in the two series being arranged in a staggered manner relatively to each other, 5 so that packages of greater width than the distance between the opposed inner runs of the said belts will have its ends to which adhesive has been applied held down by the conjoint action of the belt on one side 10 and a roller on the other side.
2. In apparatus according to claim 1, spindles on which said belt pulleys are mounted, slotted extensions on the apparatus adapted to receive the spindles of the 15 belt pulleys at one end of the said apparatus and means for securing the said spindles in any desired position in the slots to adjust the tension of the said belts.
3. Apparatus for securing the folded portions of packages to which adhesive has been applied comprising a pair of endless travelling belts, pulleys carrying said belts, and spindles on which said pulleys are mounted, the said spindles at one end of 20 the apparatus being adjustably carried in slotted extensions of the said apparatus and the spindles at the other end of the apparatus having rotary motion transmitted 25 thereto so that the said endless belts are caused to travel at equal speeds; a bottom 30 running strip constituting with the endless travelling belts a channel along which the articles are conveyed by the said belts; a series of bearing rollers rotatably secured to a bar and spaced apart behind and bearing 35 against the inner run of one of the said endless belts and another series of bearing rollers rotatably mounted on studs secured to a bar and spaced apart behind and bearing 40 against the inner run of the other endless belt, the bearing rollers of the said two series being arranged in a zig-zag or staggered manner relatively to each other, in combination with means whereby the bars carrying the respective series of bearing 45 rollers can be adjustably secured to the apparatus so that the distance between the inner runs of the endless travelling belts can be adjusted.

In testimony whereof I have signed my 50 name to this specification in the presence of two subscribing witnesses.

WILLIAM ROSE.
